MACHINE FOR APPLYING PRESSURE TO
SHOE BOTTOMS

Lawrence Mawbey, Leicester, England, assignor
to United Shoe Machinery Corporation, Pat-
erson, N. J., a corporation of New Jersey

Application October 26, 1936, Serial No. 107,632
In Great Britain November 11, 1935

38 Claims.

(Cl. 12—33)

This invention relates to improvements in shoe machines and is herein illustrated as embodied in a machine for applying pressure to shoe bottoms of the type disclosed in Letters Patent of the United States No. 2,047,185, granted July 14, 1936 on an application filed in the names of Milton H. Ballard et al.

The machine of the patent referred to may be provided with pressure applying devices or pad boxes particularly adapted for operating on men's shoes in the manner disclosed in United States Letters Patent No. 2,005,755, granted June 25, 1935 on an application filed in the name of Francis J. Better and in Letters Patent of the United States No. 2,063,041, granted December 8, 1936 on an application filed in the name of Lloyd G. Knowles. The pad boxes disclosed in the two last-mentioned patents are provided with mechanisms for relatively locating a sole and a shoe upon the pad of the machine and the latter is arranged to press the shoe and sole together to cause the sole to become secured to the shoe by cement. For the sake of brevity the term shoe is used herein as including both boots and shoes.

As shown and described in the Ballard et al. patent the machine for applying pressure to shoe bottoms has a turret arranged to rotate in a horizontal plane and carrying a plurality of shoe pressing pads arranged with their longer axes extending in the direction of rotation of the turret. The pressing faces of the pads face upwardly and each pad has associated therewith a set of sole and shoe locating means carried by the turret for relatively locating soles and shoes placed on the pads.

The mechanism disclosed in the Ballard et al. Patent No. 2,047,185 for relatively locating a sole and shoe on the pad is mounted on the pad box and includes means for relatively locating the heel ends of the sole and shoe comprising in part a sole locating pin adapted to enter a hole in the central portion of the heel end of the sole, a forked member having faces disposed thereon for engaging the opposite sides of the heel end of the shoe, and mechanism for moving the pin, while it is engaging the sole, laterally of the shoe to cause the sole to move into the desired position relatively to the shoe.

The sole locating pin and forked heel engaging member have been found in practice to be particularly suited for operating on women's shoes since the heel operating portions of the soles of such shoes are usually of such a relatively flimsy nature that they do not allow the soles to

be readily positioned relatively to the shoe bottoms by members which engage the opposite edge faces of the heel portions of the soles.

On the other hand, however, the soles of men's shoes are usually of a relatively stout character and the necessity for punching a hole in the heel end of the sole for the sole locating pin and the use of the cooperating forked member in relatively locating the sole and shoe can be avoided by utilizing a pair of sole locating fingers or gauges which engage the opposite edges of the relatively thick heel portion of the sole and cooperate with a similar pair of fingers or gauges for engaging the opposite sides of the shoe itself to determine the relative positions of the sole and shoe.

A convenient arrangement of this kind is shown in the Knowles and the Better disclosures referred to above. None of the sole and shoe locating means disclosed in the patents mentioned, however, is equally suitable for operating on both men's shoes and women's shoes, including those to which Louis heels are to be attached, and this fact has, up to the present, generally necessitated the use in pressure applying machines of the type referred to of alternative pad boxes supporting different gauging mechanisms according to whether men's or women's shoes were to be operated on.

An object of the present invention is to provide improved sole and shoe locating means for use in a machine for applying pressure to shoe bottoms adapted to operate with equal efficiency on women's shoes which have sole locating holes punched in the heel end portions of their soles and which are relatively short in length, or on men's shoes the heel end portions of the soles of which have no such holes punched therein and which are relatively long. A further object of the invention is to provide a pad box having improved pad retaining means thereon of such a nature that different pads for operating either on men's or women's shoes can readily be assembled in or removed from the pad box according to whether men's shoes or women's shoes are to be operated upon.

With these objects and purposes in view, an illustrative embodiment of the invention comprises a pad box or container for a shoe receiving pad having forepart locating or gauging means similar to that disclosed in the Ballard et al. patent referred to, and having mechanism for relatively locating the heel ends of a sole and shoe generally similar to those disclosed in the Better patent and the Knowles patent, the heel

end locating mechanism being slidable relatively to its actuating mechanism lengthwise of a shoe to enable it to engage a woman's shoe or a man's shoe in substantially the same position lengthwise thereof. The pad box of the present invention, however, is provided with pivotally mounted means for supporting a pin adapted to engage a hole in the heel portion of a sole for a woman's shoe, and this supporting means is readily movable, by outward and downward swinging movement of its supporting means, to remove the pin from operative position when it is desired to operate on a man's shoe, the heel end of the sole of which is located on the pad by other means engaging the opposite edges of the sole. The arrangement of the mechanism is such that when the sole locating pin is in position for operating on a woman's shoe, the pin and the heel portion of the sole which it engages will occupy a position lengthwise of the pad which is spaced from the other locating means referred to for engaging the opposite edges of the heel portion of the sole of a man's shoe, so that the last-mentioned means will not strike the pin or the sole even if it be allowed to be actuated idly by its actuating mechanism when the pin is in use.

The pad box carries a U-shaped plate overlying the forepart of the pad to retain the pad in position in the box, the plate being normally clamped against the pad but being capable of swinging upwardly to allow the pad to be removed from the box. The pad box also carries clamping means arranged to overlie the heel portion of the pad to hold it in the pad box, which means may likewise be readily removed from over the pad to facilitate the removal of the pad from the box.

These and other features of the invention will appear more fully from the following description when read in connection with the accompanying drawings and will be pointed out in the appended claims.

In the drawings,

Fig. 1 is a plan view of a pad box embodying the invention;

Fig. 2 is a side elevation of the pad box; and

Fig. 3 is a view partly in section of the mechanism at the right-hand end of the pad box as seen from the left in Figs. 1 and 2.

The pad box is similar, in many respects, to that disclosed in the Knowles patent mentioned above and has a fixed casting 4 for supporting the rear portion of the pad and a forward casting 6 pivotally to the rear casting and angularly adjustable relatively thereto for supporting the forepart of the pad. The forepart gauging mechanism comprises a pair of sole and shoe engaging fingers carried by arms 8 and 10 similar to those described in the Ballard et al. patent, which arms are arranged in crossed relation to each other and are pivoted for free vertical movement on the angularly adjustable casting 6 of the pad box. The arms 8 and 10 are relatively long and have gages thereon arranged to engage the opposite sides of the sole of a shoe on the pad within the box substantially at, or a little forward of, the tip line of the shoe. These arms or fingers are arranged to be swung inwardly towards each other to engage the edge face of the sole by mechanism which may be the same as that disclosed in the Ballard et al. patent.

The casting 4 of the pad box is provided at its right-hand end, as viewed in Fig. 1, with a vertical T-shaped guideway 12 in which an end wall 14 carrying a horizontal outwardly extending bracket 16 (Figs. 2 and 3) is mounted for vertical

sliding movement, the bracket being maintained yieldingly in a proper heightwise position by compression springs 18 mounted in the casting 4 and engaging the end wall 14. For relatively positioning the heel end portions of a sole and a man's shoe on a pad in the pad box, the illustrated mechanism is provided with a pair of sole engaging fingers 20, one of which is shown in Fig. 2, for engaging the opposite edges of the heel end portion of the sole and it is also provided with a pair of shoe-engaging fingers 22 for engaging the opposite side portions of the heel end of the shoe, these two pairs of fingers being somewhat similar in construction to those described in the Better patent referred to, being similarly supported upon the outwardly extending bracket 16, and being operated respectively through slide members 21 and 23 similar to those described in said Better patent as being actuated by a lever 25 (Fig. 1) and a link 27, the sole engaging fingers 20 being closed upon the sole prior to the positioning of the shoe on the sole and the shoe engaging fingers 22 being later automatically closed upon the shoe and then acting to centralize the shoe relatively to the sole.

The two pairs of fingers of the present embodiment for engaging the heel ends of the sole and shoe occupy positions lengthwise of the pad box which are well suited for operating on men's shoes the foreparts of which extend between the sole engaging fingers at the forepart of the sole and the heel end portions of which may extend well over the heel end of the pad.

To enable the present construction readily to be arranged to operate effectively on women's shoes, which are shorter than men's shoes, the pad box is provided with pivoted means for supporting a sole locating pin 24 (similar to the pin referred to in the Ballard et al. patent except that it is relatively stationary when in operative position) arranged to enter a hole in the heel end portion of the sole of a woman's shoe and thereby to maintain the sole in a definite but adjustable position on the pad, said supporting means being readily swingable in such a manner as to remove the pin 24 from its operative position when men's shoes are to be operated on for which the use of the pin is not required.

In the illustrated construction the supporting means comprises a bracket 26 projecting forwardly from the outwardly extending bracket 16 and having journalled in its forward end a pin 28 lying lengthwise of the pad box. A bell crank lever is secured on this pin 28 and an upwardly extending arm 30 of this lever is maintained, forwardly of the pad box, in a definite substantially vertical position by a spring 32 (Fig. 3) which rocks the lever rearwardly until a rearwardly extending arm 34 on the bell crank lever abuts against the upper end of a vertical screw 36 threaded through the bracket 26. A horizontal pin 38 projects lengthwise of the pad box from the upper end of the upwardly extending arm 30 and on this pin is freely mounted a two-part arm indicated generally in Figs. 1 and 3 by the numeral 40 for supporting the sole-locating pin 24. When the pin 24 is to be used, the two-part arm 40 extends rearwardly from its pivot 38 substantially horizontally and the pin 24 which it supports (in the manner hereinafter to be described) then lies in contact with the operative face of the pad about 2 inches forwardly of its heel end and about midway between its opposite sides i. e., about midway between the shoe locating fingers 22 for the heel end of a shoe. By rotating the vertical

screw 36 aforementioned, the pin 24 can be moved laterally towards one side of the pad or the other to adjust the position of the sole it engages into the desired widthwise position relatively to a shoe placed thereon. An easily releasable latch 42 pivoted on the bracket 26 snaps over a lug 44 on the two-part arm 40 to hold the pin 24 temporarily against upward movement from its operative position over the pad. By releasing the latch 42 from the lug 44 the two-part arm 40 can be swung first upwardly and then outwardly and downwardly about the pivot 38 to carry the pin 24 from its operative position over the pad to a position in which the two-part arm 40 depends idly downwards from its pivot 38 (as shown in broken lines in Fig. 3) at the forward side of the pad box, the pin 24 then being completely removed from a position over the pad in which it might interfere with the sole locating action of the heel end sole locating fingers 20 on a man's sole.

The sole locating pin 24 projects downwardly from the toeward end of a relatively thin tongue 46 which is secured at its heelward end to the lower end of a substantially vertical stem 48 which extends downwardly between the locating fingers for the heel end of the shoe and is mounted, on a pivot 50 (Fig. 3) extending widthwise of the pad, to a downwardly turned end portion of the two-part arm 40, the stem 48 being urged by a torsion spring 52 in a direction to lower the pin 24 into engagement with the surface of the pad until a pin 54 on the stem 48 abuts a fixed stop 56. The upper end of the stem 48 provides a handle by which the stem may be swung about its pivot 50 to lift the pin and allow the heel end of the sole for a woman's shoe to be placed beneath it on the pad.

In order that the position of the pin 24 lengthwise of the pad may be varied to suit soles for women's shoes of varying lengths, the two-part arm 40 comprises two superposed portions, a lower portion 58, which is secured to the pivot 38 of the arm, and an upper portion 60 which is arranged to be swung in directions lengthwise of the pad box over the lower portion 58 in such a manner that the pin 24 moves in a straight line extending lengthwise of the pad box.

For this purpose the lower portion 58 has a pin 62 extending upwardly from its forward end through a slot 64 (Fig. 1) in the forward end of the upper portion 60 of the two-part arm. The lower portion 58 of the arm has a curved slot 66 (Fig. 1) extending lengthwise of the pad box formed in its rear end and a pin 68 fast in the upper portion 60 of the arm substantially midway of its length engages the curved slot and rides along said slot as the upper portion 60 of the arm is swung about the pin 62 passing through the slot at its forward end. The shape of the curved slot 66 is such that the upper portion of the arm is moved lengthwise of itself as it is swung about the pin 62 just sufficiently to cause the sole-locating pin 24 to move in the desired straight line.

Thus it will be seen that the two-part arm 40 supporting the sole-locating pin 24 may extend horizontally and rearwardly in such a position over the pad that the pin lies more or less centrally of the heel portion thereof and an adjustable distance toewardly of the heel end of the pad so that the pin is located in a suitable position to engage holes in the heel portions of women's soles of different lengths, the foreparts 70 of which are in suitable positions to be engaged

by the forepart gauging mechanism referred to above. The arm 40 may also be swung upwardly, outwardly, and downwardly, in a plane perpendicular to the length of the pad box, to move the pin into an inoperative position, remote from the operative face of the pad. It will also be understood that, when in its operative position, the pin 24 is stationary although adjustable both lengthwise and widthwise of the pad box, and is therefore able to maintain the heel end of the sole 10 of a woman's shoe, whatever be the length of the latter, in a convenient fixed position for the shoe-locating gauges 22 for operating on the heel portion of the shoe to position the shoe in the desired manner over the heel portion of the sole. 15

In order that the heel end shoe locating or gauging fingers 22 of the present construction may conveniently be arranged to engage the heel portion of a woman's shoe in a position along the shoe corresponding to that in which they engage 20 a man's shoe, so that they may readily move the woman's shoe into the correct position relatively to the sole on the pad, the mechanism is provided with means whereby the shoe locating fingers 22 may be adjusted lengthwise of the pad relatively 25 to their actuating mechanism.

For this purpose the shoe locating fingers 22 are formed separately from intermeshing gear segments 70, 72 (Fig. 1), corresponding to the segments disclosed in the Better patent referred 30 to and the fingers are adjustable lengthwise of the pad box relatively to these segments. Each locating finger comprises a flat bar 74 extending lengthwise of the pad and underlying an extension 76 projecting towards the toe end of the pad 35 box from the outer end of each gear segment. The portions of the bars 74 more remote from the end of the pad box i. e., their right-hand portions, as viewed in Fig. 1, have slots 78 formed therein into which extend pins 80 depending from the 40 gear segments. The extensions on the gear segments have secured to the underside of their left-hand ends, depending lugs 82 which are cut away on their inner sides to provide horizontal grooves which the outer sides of the flat bars 74 45 comprising the fingers enter, relatively fixed leaf springs 84 being provided to bear against the inner edges of said bars and thereby to urge them outwardly into the grooves in the lugs 82. The pin and slot connections 78, 80 between the gear 50 segments 70, 72 and the right-hand ends of the fingers 22, and the engagement of the fingers with the lugs 82 on the gear segments constitute means whereby the gear segments 70, 72 and fingers 22 are coupled positively together for swinging movement to position a shoe relatively to its sole. 55

Also by reason of the fact that the bars 74 constituting the fingers are coupled to their respective gear segments only by the pin and slot connection and the grooved lugs 82, the fingers can 60 be moved lengthwise of the pad box relatively to their gear segments, the slots 78 in the bars tracking along the pins 80 in the gear segments and the bars sliding along the grooves in said lugs. The bars may each conveniently have cut in their 65 outer edges a notch 86 of a width corresponding to the width of the grooved lugs 82, these notches being positioned near the left-hand ends of the bars.

When the bars 74 are adjusted lengthwise of 70 the pad box so that these notches 86 lie opposite the grooved lugs 82 the leaf springs 84 cause the notches to embrace the lugs and therefore to hold the bars against movement relatively to their gear segments lengthwise of the pad box. These 75

notches conveniently occupy such positions in the bars that when they embrace the lugs 82 the shoe-engaging ends 22 of the bars occupy positions adjacent to the heel end of the pad, as indicated in Fig. 1, so that they lie in a convenient position to engage the heel portion of a man's shoe.

The bars 74 each have another notch 88 (Fig. 1) cut in their outer edges, these second notches 10 being spaced further from the shoe-engaging ends of the bars and being located about two inches away from the notches 86 first mentioned. By swinging the shoe-engaging ends of the bars inwardly a short distance towards each other relatively to their gear segments against the action of their leaf springs 84, the notches 88 are withdrawn from locking engagement with the grooved lugs 82 and the bars can be slid forwardly towards the toe end of the pad sufficiently to bring the second notches 88 in position to embrace the notched lugs 82 when the bars are released.

The shoe engaging ends 22 of the bars will then occupy positions some two inches nearer the toe end of the pad and accordingly will overlie the pad in a position suitable for engaging the opposite sides of the heel portion of a woman's shoe mounted on the pad. The same arrangement of gear segments and notched bars is provided for adjusting the sole engaging fingers 20 longitudinally of the pad.

It will therefore be understood that when it is desired to use the pad box for operating on women's shoes, the bars 74 for the shoe locating gauges 22 will be slid relatively to their gear segments to cause their shoe-engaging ends to overlie the heel portion of the pad in the proper position, and the two-part arm 40 carrying the sole-locating pin 24 will be swung from its depending position into its rearwardly extending horizontal position in which the sole-locating pin also lies over the pad between the shoe-engaging ends of the bars, the pin being adjusted both widthwise and lengthwise of the pad, if necessary, to cause it to engage the hole in the heel end of the sole and to position the latter in the desired relation to the shoe which is later engaged by the automatic closing of the shoe-locating fingers 22. The sole locating fingers or gauges 22 should at this time be adjusted into their heelward or right-hand positions so as not to interfere with the operation of the sole-locating pin 24.

When the pad box is to be used for men's shoes the two-part arm 40 will be swung away from the surface of the pad into its depending position shown in Fig. 3 and the members or bars 74 of the shoe engaging fingers 22 will then be slid back away from over the heel portion of the pad into their original positions to adapt them for cooperating with the sole locating fingers 20 for engaging the longer heel end portions of men's shoes and soles.

It may be desired to use the present pad box for operating on relatively short shoes, such as children's shoes, the soles of which have no holes punched in their heel ends. Under these circumstances the shoe-engaging fingers 22 at the heel end of the pad box are slid towards the toe end of the pad into the positions they occupy for operating on women's shoes. Since the soles have 65 no holes in their heel portions, however, the two-part arm 40 carrying the sole-locating pin 24 is allowed to remain in its depending position and both pairs of locating fingers at the heel end of the pad box are slid toewardly relatively to their gear segments until the pair of notches 88 in the

bars 74 engage the grooved lugs 82. The sole- and shoe-locating fingers are then both overlying the heel end of the pad, the shoe-locating fingers 22 lying directly over the sole-locating fingers just as they do when the pad box is to be used for 5 operating on men's shoes.

The pad box is deep enough to support both a fluid-filled shoe-engaging pad and a pair of flexible rubber blocks or pads forming a bed on which the fluid-filled pad rests, one of the rubber pads 10 underlying the forepart portion of the fluid-filled pad and the other underlying the heel portion of said pad.

It is desirable that fluid-filled pads of different sizes or shapes be used in the pad box according 15 to whether the pad box is to be used for attaching soles to men's or to women's shoes, the different pads being conveniently of the same overall dimensions but having, for example, different 20 lengthwise and transverse curvatures on their sole-engaging faces to simulate more closely the contours of the bottoms of men's and women's shoes as the case may be.

In order to allow the pad in the pad box to be 25 rapidly removed and replaced by another pad which is more suitable for operating on another kind of shoe, the illustrated pad box is provided with means which, although it acts normally to hold the pad firmly in position in the pad box, 30 can readily be moved into a position that will allow the pad to be easily and quickly removed from the box.

For this purpose the pad box carries on the 35 casting 6 (Figs. 1 and 2), which houses the forepart portion of the pad, a pair of superposed substantially U-shaped plates 90, 92, corresponding to those described in the Knowles patent above referred to, the lower plate 90 bearing against the margin of the forepart of the pad to hold it firmly on its bed. Interposed between the two plates is a two-part mask plate 94, which, as pointed out in the patent just mentioned, is adjustable lengthwise and widthwise of the pad 45 box between the plates to adapt the pad box for operating on shoes of different sizes.

In order to allow the several plates to be moved away from their pad-clamping position to facilitate removal of the pad from the box, the 50 plates are pivotally mounted on horizontal shafts 96 extending widthwise of the pad at positions beyond the toe end of the pad and substantially on the same level as the plane of the sole-engaging face of the toe end of the pad. 55

The plates normally occupy a position about the shafts 96 in which they press downwardly against the opposite margins of the pad. To hold the plates in this position there is secured on 60 each of the opposite sides of the pad box, an upwardly extending pivot pin 98 on which is freely rotatable a plate clamping finger 100 which is held against vertical movement. Each of the fingers 100 has an inwardly projecting portion arranged 65 to overlie the upper plate 92 near the right-hand end of the latter and, by engagement with this plate, to hold the lower plate 90 pressed against the pad. A bifurcated ear 102 extends to the right from each clamping finger and a screw 104 freely 70 pivoted on a vertical pin 106 also fast in the pad box is arranged to extend through the ear 102 and, by means of a nut 108 on its outer end, to act normally to prevent the clamping finger 100 from being swung about its pivot 98 in a direc- 75

tion to remove its inwardly projecting portion from over the upper plate 92.

By slackening the nut 108 on the outer end of the screw 104, however, the screw can easily be 5 swung to one side about its pivot 106 so that the clamping finger 100 can readily be swung about the pivot 98 to move its inwardly projecting portion from over the plates. When this has been done the upper and lower plates, with the 10 masking plate 94 between them, may be swung upwardly about their supporting pins or shafts 96 to a raised position in which they are well clear of the pad so that the latter may be lifted bodily out of the box. The mask plate 94 may 15 be conveniently connected to an adjusting hand lever 110 through a link 112 which facilitates its upward movement with the plates. In order to cause the plates to bear upon a new pad assembled in the box, it is only necessary to swing them 20 downwardly into engagement with the pad and to move the two clamping fingers 100 so that their inwardly projecting portions overlie the upper plate 92. The retaining screws 104 for these fingers may then be swung between their bifurcated ears 102 and the nuts 108 tightened on the 25 screws.

The heel-end portion of the pad box has secured to it a thin metal frame 114 (Fig. 2) which extends around this portion of the pad and has 30 flanges 116 extending from its opposite side portions which overlie the opposite side margins of the heel portion of the pad. At its front and rear sides, as viewed in Fig. 1, and near its heel end, the pad box has vertical pins 118 secured to 35 it, on each of which is freely rotatable a clamping finger 120 of the same kind as that which engages the upper plate 92 at the forepart of the pad. These latter clamping fingers 120 have inwardly extending portions arranged to overlie 40 the flanges 116 on the metal frame 114 and thus to hold the heel portion of the pad firmly on its bed. These clamping fingers 120 have bifurcated ear portions 122, engaged by swinging retaining screws 124 provided with nuts 126, similarly 45 to the clamping fingers previously described.

Thus it will be understood that the pad is retained in place within the box by four clamping fingers, two arranged to clamp the forepart portion 50 of the pad against the pad bed, through the superposed plates aforesaid, and two arranged to clamp the heel portion of the pad against the bed.

Although these clamping fingers are normally retained in operative position by their retaining 55 screws, these latter can readily be swung aside to allow the clamping fingers to be moved to an inoperative position relatively to the plates so that when the superposed plates have been raised the pad can readily be lifted out of the box and another pad of a different shape or size substituted therefor.

Having thus described the invention, what is claimed as new and desired to secure by Letters Patent of the United States is:

65 1. A pad box for use in applying pressure to shoe bottoms provided with a sole receiving pad, means having a predetermined angular relation to the pad when in an operative position and urged toward the pad under pressure for locating a sole relatively thereto, and means for permitting the sole locating means to be swung into a depending position remote from the pad when said locating means is not to be used, said last-named means being also constructed and arranged to adjust the sole locating means laterally

of the pad while maintaining its predetermined angular relation thereto.

2. A pad box for use in applying pressure to shoe bottoms provided with a sole receiving pad, a member initially resting on the pad in a predetermined angular relation thereto for positioning the heel portion of a sole on the pad, means carrying said positioning member constructed and arranged to permit the swinging of said member in a plane perpendicular to the length of the pad into a depending position at one side of the pad, means for urging said member toward the pad when in an operative position, and means engaging said carrying means for adjusting the positioning member widthwise of the pad without 10 changing its initial angular relation thereto. 15

3. A pad box for use in applying pressure to shoe bottoms provided with a sole receiving pad, means initially resting in a predetermined position on the pad for positioning the heel portion 20 of a sole on the pad, supporting means for said positioning means so constructed and arranged that the positioning means may be swung laterally and heightwise of the pad from normal position into an inoperative position remote from 25 the pad, and means for locking said positioning means in its initial position when it is in use.

4. A pad box for use in applying pressure to shoe bottoms provided with a sole receiving pad, a tongue normally resting against the surface of 30 the pad for engaging a sole on the median line of its heel portion and holding the sole against movement relatively to the pad, a pair of relatively movable shoe gauges for positioning a shoe 35 relatively to the pad, and means for permitting the sole engaging tongue to be moved away from the surface of the pad into a position at one side of the pad box when the tongue is not to be used so that it will not interfere with the operation on the shoe. 40

5. A pad box for use in applying pressure to shoe bottoms provided with a sole receiving pad, means normally resting on the surface of the pad for positioning the heel portion of a sole thereon, means for adjusting said positioning 45 means relatively to the pad while it is still resting thereon, and means for swinging the positioning means transversely of the pad into a depending position at one side of the pad box, thereby removing the positioning means entirely from 50 the pad when operating on some types of shoes.

6. A pad box for use in applying pressure to shoe bottoms provided with a sole receiving pad, a tongue normally resting yieldingly against the surface of the pad for engaging the heel portion 55 of a sole and holding it in a predetermined position relatively to the pad, means for adjusting said tongue in a straight path longitudinally of the pad, and means for swinging said tongue in an arc located at right angles to the length of 60 the pad, thereby removing the tongue into an inoperative position remote from the pad when the latter is to operate on soles with which the tongue is not utilized.

7. A pad box for use in applying pressure to 65 shoe bottoms provided with a sole receiving pad, a tongue for engaging the heel portion of a sole and holding it in a predetermined position on the pad, an arm carrying said tongue, and means pivoted on the pad box for supporting said arm 70 for swinging movement heightwise and outwardly of the pad to permit removal of the tongue from operative position into an inoperative position at one side beyond the edge of the pad.

8. A pad box for use in applying pressure to 75

shoe bottoms provided with a sole receiving pad, a tongue normally engaging the pad for holding a sole in a predetermined position thereon, an arm carrying said tongue, a bell crank lever pivoted on the pad box for supporting said arm, said arm being pivoted to one arm of said lever, and means cooperating with another arm of said lever for adjusting the lever about its pivot, thereby varying the initial position of the tongue laterally of the pad.

9. A pad box for use in applying pressure to shoe bottoms provided with a sole receiving pad, a tongue resting normally on the surface of the pad for engaging the heel portion of a sole and holding it in an approximately central position laterally of the pad, a pair of relatively movable shoe gauges for positioning a shoe relatively to the pad, said gauges extending longitudinally of the pad along opposite sides of the tongue, and means for supporting the tongue in its central position between the shoe gauges and for moving said tongue out of said position into a depending position at one side of the pad without interfering with said shoe gauges.

10. A pad box for use in applying pressure to shoe bottoms provided with a sole receiving pad, a tongue resting normally on the surface of the pad for engaging the heel portion of a sole and holding it in an approximately central position laterally of the pad, a pair of equally and oppositely movable shoe gauges for positioning a shoe relatively to the pad, said gauges extending longitudinally of the pad at opposite sides of the tongue, means for supporting the tongue in said central position between the shoe gauges, and means for adjusting said tongue relatively to said shoe gauges.

11. A pad box for use in applying pressure to shoe bottoms provided with a sole receiving pad, a tongue normally resting against the sole engaging surface of the pad for engaging the heel portion of a sole and holding it in a predetermined position relatively thereto, a swinging arm extending transversely over the surface of the pad for supporting said tongue, said arm being arranged to swing laterally of the pad in a plane perpendicular to the length of the pad to remove the tongue from its operative position to an inoperative position, and means for swinging said arm in a plane parallel to the sole engaging surface of the pad to adjust the tongue longitudinally thereof.

12. A pad box for use in applying pressure to shoe bottoms provided with a sole receiving pad, a tongue normally resting against the sole engaging surface of the pad for engaging the heel portion of a sole and holding it in a predetermined position relatively thereto, a swinging arm extending transversely over the surface of the pad for supporting said tongue, said arm being arranged to swing laterally of the pad in a plane perpendicular to the length of the pad to remove the tongue from its operative position to an inoperative position, means for swinging said arm in a plane parallel to the surface of the pad to adjust the tongue longitudinally of the pad, and means for simultaneously moving the arm lengthwise of itself to prevent lateral movement of said tongue during the longitudinal adjustment.

13. A pad box for use in applying pressure to shoe bottoms provided with a sole receiving pad, a pair of gauges for positioning an end portion of a shoe relatively to the pad, and means for lengthening or shortening each gauge at will 75 and independently of the other gauge to permit

them to operate successively on shoes of different lengths.

14. A pad box for use in applying pressure to shoe bottoms provided with a sole receiving pad, a pair of relatively movable gauges for positioning an end portion of a shoe relatively to the pad, and means for adjusting the work-engaging ends of said gauges into a plurality of predetermined positions longitudinally of the pad to enable them to operate on shoes of different sizes. 10

15. A pad box for use in applying pressure to shoe bottoms provided with a sole receiving pad, gauges for positioning an end portion of a shoe relatively to the pad, means for operating said gauges, means for changing the operative lengths 15 of the gauges at will without interfering with said operating means, and means for automatically determining the adjusted positions of the gauges.

16. A pad box for use in applying pressure to 20 shoe bottoms provided with a sole receiving pad, gauges for positioning a sole and shoe relatively to each other on the pad, adjusting means for lengthening or shortening the gauges into predetermined positions lengthwise thereof to adapt 25 them for operating on shoes of different sizes, and means for automatically maintaining the gauges in predetermined adjusted positions.

17. A pad box for use in applying pressure to 30 shoe bottoms provided with a sole receiving pad, gauges for positioning an end portion of a sole on the pad, separate gauges for positioning a shoe relatively to the sole on the pad, and means for varying the effective lengths of the gauges predetermined amounts to permit them to operate 35 successively on shoes of different lengths.

18. A pad box for use in applying pressure to shoe bottoms provided with a sole receiving pad, gauges for relatively positioning a sole and shoe on the pad, means for simultaneously swinging 40 said gauges laterally toward and from the sole and shoe, and means for lengthening or shortening said gauges relatively to said swinging means to adapt the gauges for operating on both large and small shoes. 45

19. A pad box for use in applying pressure to shoe bottoms provided with a sole receiving pad, laterally movable gauges for relatively positioning the heel portions of a sole and shoe on the pad, means for adjusting the gauges longitudinally of the pad to permit them to operate successively on shoes of different lengths, and spring means for holding the gauges in adjusted positions. 50

20. A pad box for use in applying pressure to 55 shoe bottoms provided with a sole receiving pad, means for relatively locating one type of sole and shoe on the pad, means for relatively locating a different type of sole and shoe on the pad, and mechanism permitting removal of either locating means from operative position when the other locating means is in use. 60

21. A pad box for use in applying pressure to shoe bottoms provided with a sole receiving pad, gauges for locating a shoe relatively to a sole 65 positioned on the pad, means for moving said shoe gauges bodily lengthwise of the pad, and separate means for varying the effective lengths of said gauges lengthwise of the pad.

22. A pad box for applying pressure to shoe 70 bottoms provided with a sole receiving pad, means for positioning the heel portion of a sole on the pad, a pair of gauges interconnected for positive movement equal amounts in opposite directions for positioning a shoe on the sole, mechanism for 75

- operating said gauges in said manner, and means for varying the operative positions of the work engaging ends of the gauges predetermined distances lengthwise of the pad without changing the relation of the gauges to said operating mechanism, thereby permitting the gauges to operate on shoes of different lengths.
23. A pad box for applying pressure to shoe bottoms provided with a sole receiving pad, a pair of gauges for positioning a shoe relatively to the pad, mechanism for effecting equal and opposite movement of the gauges, and connections between said gauges and said mechanism permitting the work engaging ends of the gauges to be adjusted longitudinally of the pad into a plurality of positions for operating on shoes of different lengths.
24. A pad box for use in applying pressure to shoe bottoms provided with a sole receiving pad, a pair of gauges for positioning a shoe on the pad, each gauge having a plurality of notches thereon located at different positions lengthwise of the gauge, intermeshing gear segments supporting said gauges for movement relatively thereto and operable to produce equal and opposite movement of the gauges, a lug on each gear segment provided with a groove, and means constantly urging each gauge toward its corresponding lug to cause one of the notches on the gauge to embrace the groove in the lug when the two are moved into alignment with each other by movement of the gauge relatively to its segment, thereby locating the gauges in different positions relatively to the pad.
25. A pad box for use in applying pressure to shoe bottoms provided with a sole receiving pad, means for locating a relatively large sole on the pad, separate means for locating a medium size sole on the pad, and means for moving either of said sole locating means out of operative relation to the pad when the other locating means is in use.
26. A pad box for use in applying pressure to shoe bottoms provided with a sole receiving pad, means for locating a relatively long sole on the surface of the pad, separate means for alternatively locating a medium length sole on said surface, means for locating a shoe relatively to the pad, and means for moving said shoe locating means into position to cooperate with either of said sole locating means.
27. A pad box for use in applying pressure to shoe bottoms provided with a sole receiving pad, means for locating a relatively long sole on the surface of the pad, separate means for alternatively locating a medium length sole on said surface, a pair of relatively movable members for locating a shoe relatively to the pad, means individual to the shoe locating members for adjusting them longitudinally into a position for operating upon either a long shoe or a short shoe depending upon the type of sole on the pad, and means for moving the non-operating sole locating means into a position remote from the surface of the pad.
28. A pad box for use in applying pressure to shoe bottoms provided with a sole receiving pad, a pair of gauges for locating a relatively long sole on the pad, a tongue for locating a shorter sole on the pad, a single pair of shoe gauges for locating shoes of all lengths relatively to the pad, means for adjusting said shoe gauges lengthwise of the pad to bring them into cooperating relation with either the tongue or the sole gauges, means for moving the sole gauges longitudinally of the pad out of operative relation thereto when the shoe gauges are cooperating with the tongue, and means for swinging the tongue heightwise of the pad into a position remote from the pad when the shoe gauges are cooperating with the sole 5 gauges.
29. A pad box for use in applying pressure to shoe bottoms provided with a sole receiving pad, gauges for positioning the heel portion of a sole on the pad, gauges for positioning the heel portion of a shoe relatively to the pad, means for adjusting said sole gauges lengthwise of the pad to permit them to operate on soles of different lengths, separate means for adjusting the shoe gauges longitudinally of the pad in accordance 10 with the position of the sole gauges, and means for adjusting the sole and shoe gauges as a unit 15 longitudinally of the pad.
30. A pad box for use in applying pressure to shoe bottoms provided with a sole receiving pad, a pair of gauges for positioning a sole on the pad, intermeshing gear segments supporting said sole gauges and operable to move them equal amounts in opposite directions, a separate pair of gauges for positioning a shoe relatively to the pad, 20 intermeshing gear segments supporting said shoe gauges and operable to move them equal amounts in opposite directions, and means for adjusting either gauge of each pair relatively to its gear segment and independently of the other gauges. 25
31. A pad box for use in applying pressure to shoe bottoms provided with a sole receiving pad, a tongue for locating the heel portion of a medium length sole relatively to the pad, a pair of sole gauges adjustable longitudinally of the pad for 30 locating either a relatively long sole or a relatively short sole on the pad, and a pair of shoe gauges for locating a shoe of any size relatively to the pad, said shoe gauges being adjustable independently of said tongue and said sole gauges and 35 being movable into positions to cooperate with said tongue for medium length shoes, or to cooperate with the sole gauges when the latter are positioned for operating on relatively long soles or are positioned for operating on relatively short soles. 40
32. A pad box for use in applying pressure to shoe bottoms provided with a sole receiving pad, a tongue normally resting on the pad for positioning the heel portion of a sole on the pad, a pair of shoe gauges located at opposite sides of the 45 tongue and movable equal amounts in opposite directions for positioning the heel portion of a shoe relatively to the pad, means for adjusting the tongue longitudinally and laterally of the pad relatively to the shoe gauges, means for varying the 50 operative lengths of said shoe gauges at will and independently of the tongue, and means for normally supporting the tongue between said shoe gauges but permitting said tongue to be swung away from the pad into a position remote from 55 the shoe gauges.
33. A pad box for use in applying pressure to shoe bottoms provided with a sole receiving pad, means fulcrumed on the pad box for pivotal movement relatively thereto for confining the 60 pad therein, means carried by the pad box for securing said confining means in operative position, and means for permitting said securing means to be readily removed from securing relation to said confining means, thereby permitting 65 the confining means to be moved to allow a quick interchange of pads in the pad box.
34. A pad box for use in applying pressure to shoe bottoms provided with a sole receiving pad, means for clamping the pad in the pad box, said 70
- 75

means being movable about an axis substantially parallel to the plane of the work-engaging surface of the pad, means for locking said clamping means in pad clamping position, and means for fastening said locking means in operative position, said fastening means being readily removable to release the locking means and permit swinging movement of the confining means about its axis, thereby allowing a quick removal of the pad.

35. A pad box for use in applying pressure to shoe bottoms provided with an inflatable sole receiving pad, a plate for confining the pad within the pad box, said plate being arranged to swing heightwise of the box about an axis located substantially in the plane of the sole receiving surface of the pad, a finger movable about a vertical axis for holding the plate in pad confining position, and pivoted means for engaging the finger and locking it in operative position against the plate, said pivoted means being arranged to be swung readily away from the finger to free the latter and permit movement thereof about its vertical axis away from the plate, thereby releasing the plate for movement heightwise of the pad box and allowing a quick interchange of pads.

36. A pad box for use in applying pressure to shoe bottoms provided with a pad having a sole receiving surface thereon, means overlying the margin of said surface for confining the pad in the pad box, said means being arranged to swing

about an axis located substantially in the plane of said surface, means on opposite sides of the pad box for engaging the pad confining means and holding it in operative position, and readily removable means for fastening said holding means in operative relation to the confining means, thereby permitting a quick release of the holding means to allow the pad confining means to be swung out of operative position and to permit a quick removal of the pad and the introduction of 10 a pad of a different type.

37. A pad box for use in applying pressure to shoe bottoms provided with a sole receiving pad, gauges for locating a sole on the pad, means for varying the effective lengths of said gauges to 15 adapt them for operating on either long or short soles, separate means for locating a sole of intermediate length on the pad, and means for removing either the sole gauges or the sole locating means from operative position relatively to the 20 sole when the other locating means is in use.

38. A pad box for use in applying pressure to shoe bottoms provided with a sole receiving pad, gauges for positioning a sole on the pad, means for positioning a shoe relatively to the sole, arms 25 carrying said sole gauges, means for lengthening or shortening said arms to position the sole gauges for operating respectively on short and long soles, and means for permitting the shoe positioning means to cooperate with the sole gauges whether 30 their arms are lengthened or shortened.

LAWRENCE MAWBEY.
